UNITED STATES PATENT OFFICE.

MAX SCHEUER, OF NEW YORK, N. Y.

DESIGN FOR AN APPAREL-BELT.

SPECIFICATION forming part of Design No. 33,486, dated October 30, 1900.

Application filed October 3, 1900. Serial No. 31,924. Term of patent 7 years.

To all whom it may concern:

Be it known that I, MAX SCHEUER, a citizen of the United States, and a resident of New York city, county and State of New York, have invented and produced a new and original Design for an Apparel-Belt, of which the following is a specification, reference being had to the accompanying drawings, forming part thereof.

10. Figure 1 is a perspective view of an apparel-belt, showing my new design; and Fig. 2 is a sectional view taken on line 2 2, Fig. 1. As shown in the drawings, the leading feature of my design consists of a belt formed of sections *a*, connected to the rings *b* by the leaf-shaped tabs *c*. The two edges of each

5 of the tabs converge toward the front into a point *c'*, and also toward the rear, so as to fully expose the upper and lower portions of the rings. Crease-lines *c²* are formed upon 20 the faces of the tabs parallel to their edges.

What I claim is—

The design for an apparel-belt, substantially as herein shown and described.

Signed by me at New York city, county and 25 State of New York, this 2d day of October, 1900.

MAX SCHEUER.

Witnesses:

WILLIAM SCHULZ,
F. V. BRIESEN.
